UNITED STATES PATENT OFFICE.

EPHRAIM C. SOOY, OF KANSAS CITY, MISSOURI.

BALING-PRESS.

SPECIFICATION forming part of Letters Patent No. 394,623, dated December 18, 1888.

Application filed July 24, 1888. Serial No. 280,905. (No model.)

To all whom it may concern:

Be it known that I, EPHRAIM C. SOOY, a citizen of the United States, residing at Kansas City, in the county of Jackson and State of Missouri, have invented certain new and useful Improvements in Baling-Presses; and I do hereby declare that the following is a full, clear, and exact description of the same, which will enable others skilled in the art to which it appertains to make and use the same, reference being had to the accompanying drawings, forming a part of this specification.

My invention has for its object primarily to enable the initial velocity of the pitman in a horse-power press in the line of its work to be augmented by means of and within the radius of the crank prior to the application of the stroke of the crank upon the pitman to effect a compression of the material, thereby accomplishing in a short portion of a circuit described by the draft-pole a reciprocal movement of the pitman so far in the direction of the feed-receptacle as the loose material in the press will permit.

The invention consists in the novel construction and combination of parts, which will first be fully described, and specifically pointed out in the claims.

In the drawings, Figure 1 is a side elevation of a movable baling-press, showing my improved horse-power mechanism; also, a portion of the feed-receptacle and the plunger thereon. Fig. 2 is a detail side elevation of the horse-power mechanism with the feed-receptacle removed. Fig. 3 is a plan view of the horse-power mechanism, as seen in Fig. 2, showing the pitman refracted and the end extending beyond and in a parallel relation with the cranks on the shaft and in a position at the beginning of a stroke. Fig. 4 is a plan view in detail of the bed of the press with the yoke, upper portion of shaft-bearings, and shaft removed, showing the pitman, the guide and supporting rollers, and the end of the crank bearing upon the end of the pitman at the middle of the stroke. Fig. 5 is a plan view similar to that seen in Fig. 4, showing the position of the crank and pitman at the dead-center or end of the stroke. Fig. 6 represents a longitudinal sectional view of the bed of the press, the cylinder thereon, and

the pitman, showing the arms on the pitman for operating the piston in the cylinders.

In the construction of my improved horse-power mechanism and press, A represents a horizontal platform or bed, which is made narrow in width and of the desired length to support the power-shaft and feed-receptacle. Upon the extreme forward end, a, of the bed A is placed the U-shaped bearing or casting for the crank-shaft, which consists, first, of a horizontal plate, b, which extends from the extreme end, a, of the bed A a proper distance to afford the bearing for the crank-shaft toward the opposite end of the bed. From the plate b, a short distance from the extreme end, a, of the bed A, to admit the transverse axle-bearings supporting the bed and also the crank-shaft, is extended in an upward inclined direction a support, b', one portion, b², of which is bent in a horizontal relation at the upper end and extends in one direction to a point in a vertical relation above the extreme end of the portion a of the bed A, and in an opposite direction a portion, B, extends of which is a suitable distance for the reception of the crank and shaft, and upon the extreme end of said portion B is placed a journal-box, B', the cylindrical opening in which is in a vertical relation to the bed.

Directly beneath the journal-box B', in a vertical line with its opening, and in the plate b, is made a cylindrical bearing, b³. In the journal-box B' is then placed a vertical shaft, C, the lower end, c, of which rests in the bearing b³ in the plate b. Upon the shaft C, and extending radially in one direction and from directly opposite sides of said shaft, at a point on said shaft intermediate the journal-bearings B' B³, are the cranks C' C². In a transverse relation, and through the extreme ends of the cranks C' C², are made the slots c' c², and in said slots, between the portions c⁵ c⁶ of the ends of the cranks C' C², are placed in a vertical relation the anti-friction rollers c³ c⁴, which rotate on the pivots c^x c^x, which pivots extend in a vertical relation through said portion c⁵ c⁶. The upper end of the shaft C extends through and a slight distance above the shaft-bearing B', and upon said upper end of said shaft is rigidly attached in a transverse relation a yoke, D, the

opposite ends of which yoke extend at equal distances from the shaft C.

Upon one end of yoke D is pivotally attached in a horizontal relation one end of the 5 draft-pole E, which is suitably connected to a rod or brace, F, which is rigidly attached to the opposite end of the yoke D, and by means of which the shaft C is rotated.

Upon the end a' of the bed A is placed a 10 receptacle for the material to be baled, in which receptacle is placed a reciprocating plunger, II. For the purpose of obtaining the initial speed of the plunger, a pitman, I, is made of the proper length, one end of 15 which is pivotally connected to said plunger H, and the opposite end extended in the direction of the cranks $C' C^2$ so far as to permit the full extension of the plunger in the receptacle G necessary for compressing the 20 material and the operation of the cranks, constructed as hereinafter described.

To support the end of the pitman I in the direction of the cranks $C' C^2$ in a horizontal relation, two vertical supports, $k k$, are attached in a transverse relation to and upon the upper portion of the bed A, a short distance from the path of the ends of the cranks $C' C^2$, and in the direction toward the receptacle G. To the upper ends of the supports 25 $k k$ is pivotally attached the respective opposite ends $k' k^2$ of the horizontal anti-friction roller K, upon which the pitman I reciprocates. The end of the pitman, which reciprocates past the crank-shaft C, conforms in 30 shape to the human foot, the toe portion extending in an outward direction in its relation to the shaft C, and more particularly is constructed as follows:

The pitman I consists of a longitudinal bar 40 of equal thickness in a vertical relation, and to within a proper distance of the end which reciprocates past the shaft C is of a uniform width. The inner longitudinal edge portion, i , which plays near shaft C, extends in one 45 direct line from its pivotal point on the plunger H to within a short distance of its extreme opposite end, at which point, for a distance nearly one-half the circumference of the roller c^4 in the crank c^2 , a portion of said 50 end along the edge is cut away in a curved relation, as at i' . Upon the extreme end, and in the longitudinal direction of the pitman I, is made a slight curved depression, i^2 , of a proper size to receive a portion of the 55 periphery of rollers $c^3 c^4$.

From a line drawn in the horizontal direction of the pitman I, between opposite parallel edges and intersecting the depressed line of groove i^2 , the end i^3 of the pitman is 60 extended a short distance beyond the said depressed portion i^2 outwardly in relation to shaft C and in an opposite direction to the edge i' and at an obtuse angle. From the depressed portion i^2 of the end of the pitman 65 the incline is slightly ascending, and to the extreme or toe end of the pitman a short out-

ward curve, i^3 , is given to said end of the pitman. Around the toe end of the pitman the curve is made gradual, and at i^4 a return inward curve is made, the portion removed from the pitman to form said curve contracting the width of the pitman in width at point x on said pitman, which is slightly in rear of the curved portion i' on the edge i . From the contracted portion at the point x to the point 70 y on the outer edge of the pitman I is described an incline plane, i^5 , to the outer edge, i , the width of the pitman increasing in the direction of its opposite pivotal end and toward said point y , said point y being the 80 widest part of the pitman, and extends a suitable distance from the point x to enable the pitman to be checked in its rebound, as hereinafter described.

For the purpose of obtaining a lateral bearing for the vibrating end of the pitman, two longitudinal arms, $L L'$, are first made of the required length. The cranks $C' C^2$ are first turned to a position in the longitudinal direction of the bed A and the vibrating end of the 90 pitman I retracted as far as necessary past the crank C' upon the side of the bed of the press, which permits the longitudinal edge i of the pitman to nearly approach the shaft C. One end portion of the arm L is then attached 95 rigidly to the under-side portion of the support B in the following manner: Projecting laterally from the side of the support B, in a line horizontal with the under portion of the box B' and on opposite sides of said support, 100 are cast the flanges b^4 . In rear of said box B' of the support B, on the side of the bed of the press opposite to that occupied by the pitman I and to said flange b^4 , is attached rigidly, by the bolt l in a horizontal relation, one end of 105 the arm L. The said arm L is then extended to a point beyond the radius of the cranks $C' C^2$ and past the pitman I and in the direction of the point y of the incline portion of the 110 said pitman, the said arm describing nearly 115 an obtuse angle to the longitudinal plane of bed A.

Upon the bed A, directly beneath the arm L, is attached rigidly to the plate b , by means of the bolts $l' l'$, a similar arm, L' , which arm 115 L' extends in a horizontal relation at the same angle as arm L in its relation to bed A, and its extreme end to a point past the pitman I in a vertical line with the extreme outer end of said arm L. Through said arms $L L'$ 120 are made in a vertical relation the perforations $p p$, in which perforations is fitted a pivot, p , and upon said pivot is placed in a vertical relation an anti-friction roller, M, which bears upon the incline plane i^5 of the 125 outer edge of the pitman I. A lug, N, is attached rigidly to the bed A of the press at a point on the side of the supporting-roller K toward the feed-receptacle and at a point intermediate the opposite longitudinal sides of 130 the bed A of the press, which will prevent the pitman from approaching quite to the

dead-center, which lug extends in a vertical relation above the horizontal plane of the pitman I.

For the purpose of checking the rebound of the pitman I between the bearing or roller M and the longitudinal sides of the cranks C' C², the ends of which extend a slight distance outwardly on opposite sides of shaft C, at the point of connection with said shaft, a cylindrical opening, c³, is made in said ends of cranks C' C², in a transverse relation to said cranks and diametrically in relation to shaft C, and on relatively opposite sides of said shaft, in which openings are placed the rubber or wood cushions c⁷, which extend outwardly to a point slightly in advance of a line drawn tangentially from the periphery of roller c³ to the periphery of roller c⁴. For the purpose of affording additional means for preventing the rebound of the pitman, and the distance of recoil of the vibrating end in its relation to and past roller M, between the points x y on said pitman, an air-cushion or hollow cylinder, S, is rigidly attached to the upper side of the bed A of the press, extending in the longitudinal direction of and beneath said pitman, and in position is placed so far toward the shaft C as to be removed from the path of plunger H. The opposite ends of the air-cylinder S are closed with the ends s s, which are perforated in a central transverse relation and retain air under pressure of the piston. Within the cylinder S is a piston, s', and extending longitudinally through the cylinder S and the ends s s, an equal distance beyond said ends and connected rigidly with the piston s', is a piston-rod, s². To the under side portion of the pitman I and at a point close to the end of the cylinder S, toward the receptacle G, the plunger H, being retracted the desired distance from the said receptacle, is rigidly attached in a transverse relation to said pitman a depending arm, i⁶, which extends so far in a downward relation as to contact with the end of the piston-rod s². Upon the pitman I, and in the direction of its vibrating end, is rigidly attached a similar depending arm, i⁷, which extends downwardly and contacts with the end of the piston-rod s², which is extended in the direction of the shaft C, nearly to its full length, so that as the plunger H is reciprocated within the receptacle G the arms i⁶ i⁷ play alternately on the opposite respective ends of the piston-rod s². The air on opposite sides of the piston s', in either direction in which the piston is moved, compresses the air toward the ends, which slowly escapes around the piston-rod and the rebound of the pitman is gradually restrained.

One portion of the press carrying the power is shown attached to the axle o, which extends in a transverse relation between the portion a of the bed A and the portion b² of the horizontal support for shaft C, which axle is provided with the wheels P. At a point on axle o, between the traction-wheels P P, is at-

tached rigidly a post, R, which extends in a vertical relation a sufficient distance to permit the end b⁴ of the support B to rest thereon 70 and bring the plate b on bed A nearly against the under side of the axle O. A short extension of the post R, beneath the axle O, is perforated in a vertical relation, and receives a stud, r, on the plate b, and through the portion b⁴ in a vertical relation, is inserted a bolt, r', which enters a perforation, r², in the upper end of the post R, which enables the axle to be turned at an angle to the bed A. The opposite end of the press is shown unsupported, which portion may be mounted in any manner preferred.

In the operation of the press the vibrating end of pitman I is first retracted in the longitudinal direction of the end portion, a, of the press, as seen in Figs. 1, 2, and 3. The piston s', as seen in Fig. 1, being near the bottom s of the cylinder S, the material to be baled is first placed in receptacle G, and power is then applied and the yoke D and shaft C rotated in the direction of the arrows or relatively to the right. The anti-friction roller c⁴ on the end of the crank C² is then brought to bear against the inner edge, i, of the vibrating end portion of pitman I. The opposite inclined portion i', near the point y, is thrown against anti-friction roller M, (see dotted lines in Fig. 3,) and as the leverage of crank C² is increased the tendency of crank C² to turn upon its axis past stationary anti-friction roller M in the radius of driving-shaft C operates to eject the said vibrating end of pitman and the pitman I is thrown in the direction of the receptacle G, the portion of the vibrating end from the point y to the point x on the inclined plane c¹ being moved at an accelerated speed, and the plunger H forced within the receptacle G to a position in contact with the material to be compressed, and during which movement of the pitman 110 the crank c² follows the incline i', and in one quarter of its circle of rotation the roller c⁴ is in a position nearly at right angles to the pitman I and in the depression i⁸, in readiness to impart the stroke which compresses the material in the receptacle G, the foot portion of the pitman being meanwhile released from contact with roller M. Thus it may be seen that a crank may be employed comparatively short in length to effect the result described. 115 Upon another quarter rotation of the crank C the said crank and pitman are nearly at a dead-center, as seen in Fig. 5. The pitman I, held by the lug N from a direct dead-center, throws the plunger H within the receptacle 120 G and compresses the material. As soon as the compression is effected, the rotation of shaft C is past the curved portion i' of the pitman, the material under compression expands, and the plunger H and the pitman rebound instantly to a position, as seen in Fig. 3, the vibrating end of said pitman is thrown between the roller M and the shaft C to a position parallel with cranks C' C², the edge i

of the pitman contacting with the cushion c^7 , and the recoil checked when the highest point of the incline i^4 meets the roller M . In the rebound of the plunger the arm i^6 meets the end of piston-rod s^2 , and the piston slowly yielding as the air escapes serves to lessen additionally the violence of the recoil. The crank C is then operated to move the pitman, and the compression of the material repeated 10 in a corresponding manner.

It will readily be seen that the rebound of the pitman is readily checked in a light power-press between the roller M and the cushion c^7 , and the service of the air-cushion 15 is only employed as occasion requires.

Having fully described my invention, what I now claim as new, and desire to secure by Letters Patent, is—

1. In a baling-press having a suitable bed, 20 the combination, with a driving-shaft and its cranks, of laterally-extended arms provided with an anti-friction guide-roller extending beyond the radius of said cranks, a rebounding plunger, and a pitman adapted to rebound 25 within the radius of said cranks, and provided with a contracted inclined vibrating end portion adapted to come into contact with said guide-roller, as described.
2. In a baling-press having a suitable bed, 30 the combination, with a driving-shaft, of cranks provided with anti-friction end rollers, laterally-extended fixed arms provided with an anti-friction guide-roller extending beyond the radius of said cranks, a rebounding 35 plunger, and a pitman having a vibrating end portion adapted to rebound within the radius of said cranks, and an inclined outer edge portion declining toward its end adapted to come into contact with said guide-roller and 40 retain the said end of the pitman in the path of the anti-friction roller on the end of said cranks, for the purpose described.
3. In a baling-press having a suitable bed, 45 the combination, with a driving-shaft, of cranks provided with anti-friction end roller, laterally-extended fixed arms provided with an anti-friction guide-roller extending beyond the radius of said cranks, a rebounding 50 plunger, and a pitman having a vibrating end portion adapted to rebound within the radius of said cranks, an inclined outer edge portion

declining toward its end adapted to come into contact with said guide-roller and retain the said end of the pitman in the path of the end of said cranks, and a cushion on the side 55 of said cranks in a transverse relation to said driving-shaft, for the purpose described.

4. In a baling-press having a suitable bed, the combination, with a driving-shaft, of cranks provided with anti-friction end rollers, 60 laterally-extended fixed arms provided with an anti-friction guide-roller extending beyond the radius of said cranks, a rebounding plunger, and a pitman having upon its vibrating end portion an inclined edge portion 65 declining toward said end of the pitman adapted to come into contact with said guide-roller and between said guide-roller and said cranks, a depression in the end of said pitman adapted to receive the anti-friction rollers in said 70 cranks, and a lug on said bed on the relative side of said pitman opposite to said inclined end portion and at a suitable distance from the dead-center described by said cranks and pitman, for the purpose described.

5. In a baling-press having a suitable bed, the combination, with a driving - shaft, of cranks on said shaft, extending in opposite directions and provided with anti-friction end rollers, laterally-extended fixed arms provided 80 with an anti-friction guide-roller extending beyond the radius of said cranks, a rebounding plunger, and a pitman having upon its vibrating end portion an inclined edge portion declining toward said end of the pitman 85 and adapted to come into contact with said anti-friction guide-roller and between said guide-roller and said cranks, a foot portion on said end of the pitman extending to and beyond said guide-roller when retracted, a lug 90 on the said bed of said press on the side opposite to the said inclined end portion and at a suitable distance from the dead-center described by said cranks and pitman, and a cushion on the longitudinal side of said cranks 95 in a transverse relation to said driving-shaft, for the purpose described.
